UNITED STATES PATENT OFFICE.

WILLIAM D. THOMPSON, OF DETROIT, MICHIGAN, ASSIGNOR TO HUTCHINS CAR ROOF-
ING COMPANY, OF DETROIT, MICHIGAN, A CORPORATION OF MICHIGAN.

CAR-ROOF.

1,237,412.

Specification of Letters Patent. Patented Aug. 21, 1917.

Application filed January 31, 1914. Serial No. 815,741.

To all whom it may concern:

Be it known that I, WILLIAM D. THOMPSON, a citizen of the United States of America, residing at Detroit, in the county 5 of Wayne and State of Michigan, have invented certain new and useful Improvements in Car-Roofs, of which the following is a specification, reference being had thereto in to the accompanying drawings.

- 10 The invention relates to car roofs of the type known as outside roofs, in which the roof boards are covered with metallic weather-proofing sheets flexibly connected to each other.
- 15 It is the object of the present invention to provide means for securely attaching the weather-proofing sheets to the board structure and at the same time permitting freedom of adjustment to compensate for the 20 weaving and flexing of the car frame.

In the drawings:

Figure 1 is a transverse cross section through a portion of the car roof to which my improvement is applied;

- 25 Fig. 2 is a longitudinal section therethrough; and

Fig. 3 is an enlarged section through the securing bolt.

A is the board sheathing of a wooden car 30 roof, which is secured to purlins B and car-lines C. D are independently adjustable outside metallic weather-proofing sheets which extend from ridge to eaves and are arranged in series having flexible weather- 35 proof connection with each other. At the ridge these sheets are preferably provided with upstanding flanges E which are weather-proofed by ridge caps F, while at the eaves the sheets extend beyond the side 40 plates of the car and are provided with downturned flanges G.

To firmly secure these sheets to the car roof and yet to provide freedom for adjustment, I connect to each of the sheets, 45 preferably centrally thereof and adjacent to the side plate of the roof frame, a bolt or pivot member H, and this, as shown, engages a raised boss I upon the sheet and is secured thereto by a riveted head J. Below

the sheet the bolt is of cylindrical form and 50 passes through an aperture in the board A and preferably also through an alined aperture in a bracket K suitably secured, as by attachment to the side plate F', by bolts L. The bolt H is also preferably provided with 55 a shoulder M and a nut N engaging a threaded shank beyond this shoulder, by which the nut may be locked without clamping the sheet to prevent the pivotal movement of the bolt.

With the construction as described in use, 60 each of the sheets D is free to adjust itself about the axis of the pivot H, and by reason of the loose engagement with the adjacent sheets and also at the ridge and eaves, perfect freedom within certain limits is provided.

What I claim as my invention is,—

1. In an outside car roof, the combination 70 of a weather-proofing sheet, a pivot non-rotatively secured to said sheet and depending therefrom, and means for securing said pivot to the under roof, said means permitting the limited rotation of said weather proofing sheet.

2. In an outside car roof, the combination 80 of a weather-proofing sheet extending from ridge to eaves, a pin secured centrally and non-rotatively to said sheet and depending therefrom, and a bearing upon the under roof in which said pin is rotatively secured.

3. In an outside car roof, the combination 85 of a weather-proofing sheet having a boss formed thereon, a pin non-rotatively secured to said boss and depending therefrom, a supporting board roof for said sheet through which said pin passes, and securing means between said pin and roof permitting rotative movement.

4. In an outside car roof, the combination 90 with a weather-proofing sheet having a boss formed thereon, of a pivot member secured to said boss and depending therefrom, a supporting board roof for said sheet and a bracket beneath said board 95 roof, said board roof and bracket having alined apertures therethrough and said pivot member extending through said aper-

tures, the portion of said pivot member extending through said bracket being of reduced size, and a nut engaging said reduced sized portion loosely securing said pivot member to said bracket.

5. In an outside car roof, the combination of a weather-proofing sheet, a pivot secured to said sheet attachable and detach-

able therewith, and detachable means for securing the pivot to the under roof.

10

In testimony whereof I affix my signature in presence of two witnesses.

WILLIAM D. THOMPSON.
